BRAKE SHOE

Fitz William Sargent, Mahwah, N. J., assignor
to The American Brake Shoe and Foundry
Company, Wilmington, Del., a corporation of
Delaware

Application March 7, 1931. Serial No. 520,878

3 Claims. (Cl. 188—243)

This invention relates to improvements in brake shoes and its object is to reduce the vibration and relative movement of the shoe on the head and thereby avoid the wear of contacting parts incident to such vibration and movement; and also to hold the shoe tightly on the head and thereby reduce the liability of fracture and better ensure holding the parts together in case of fracture to prolong the life and service of the shoe.

Brake heads are usually made of malleable iron or mild steel which are tough and strong metals and resist tensional and torsional stresses, but because of the comparative softness of these metals they will abrade by rubbing contact so that in the course of time the parts of the head which support the shoe will wear and loosen the mounting and reduce the efficiency thereof and increase the liability of the shoe and head to fracture, requiring replacement before the head or the shoe has otherwise reached its limit of service. The vibration of the shoe and the head in service is largely the cause of wear of parts and this is increased materially as wear produces looseness in the mounting and particularly when the key loosely connects the shoe and head. The shoe will be held tightly on the head when the brake is applied by reason of the brake pressure, but the key should hold the shoe tightly on the head when the brake is not in action and when the brake is being applied. If the key holds the shoe loosely on the head when the brake is not in action, the shoe will hang more or less free on the head and will move and rattle around on the head causing excessive wear of the brake head-lug on which the shoe rests as well as on the attaching lug, due to the vibration of the shoe and head when the car on which they are mounted is moving and especially during switching operations; and this wearing action increases rapidly as the shoe becomes looser on the head and permits a slight bending of the reinforcing back in the shoe when the body of the shoe fractures, finally resulting in the back breaking and permitting parts of the body to fall away and consequent premature destruction of the shoe.

My invention aims to reduce the relative movement of the shoe and head and thereby prevent the excessive wear of their contacting parts and the damage to the shoe and the head which results therefrom, thereby prolonging the life of the shoe and the head and increasing the efficiency of the shoe.

The invention is adapted for heads and shoes of different types, including flanged and unflanged shoes, and I have selected to illustrate the invention a simple type of car shoe in the accompanying drawings in which

Fig. 1 is a side elevation of a shoe partly in

section mounted on a head which is partly broken away.

Fig. 2 is a transverse sectional view of the shoe on the line 2—2 of Fig. 1.

Fig. 3 is a transverse sectional view of the shoe and head on the line 3—3 of Fig. 1.

Fig. 4 is a fragmentary view showing another embodiment of the invention.

Fig. 5 is a transverse sectional view of the shoe on the line 5—5 of Fig. 4.

Fig. 6 shows another embodiment of the invention.

Fig. 7 is a transverse sectional view of the shoe on the line 7—7 of Fig. 6.

Fig. 8 shows another embodiment of the invention.

Fig. 9 is a transverse sectional view of the shoe on the line 9—9 of Fig. 8.

Referring to the drawings the shoe 10 is provided with end lugs 9, an attaching lug 11 and a suitable reinforcing back 12. The head 13 has two lugs 14 spaced apart to receive the attaching lug 11 of the shoe. The lug 11 and the lugs 14 have openings 11' and 14' respectively extending lengthwise of the shoe and head and constituting keyways to receive the key 15. Provision is made for customary clearance between the lugs 11 and 14 of the shoe and the head, which are castings, and the openings in the lugs are made by the use of cores without machining. There is generally some looseness of fit between the shoe and the head and while the key will hold the shoe on the head it will not always hold it tightly and because of the clearance between the lugs and the vibrations in service the lug of the shoe will wear on the lug of the head upon which it rests and sooner or later cause such an excessive looseness in the mounting of the shoe on the head that damage to the shoe will result. To avoid these disadvantages the shoe is provided with bosses 16 spaced from the attaching lug 11 to receive the head lugs 14 between themselves and the attaching lug, Fig. 1. The bosses should be located close to the head lugs and should project slightly beyond the outer walls of the openings 14' in the head lugs when the shoe is mounted on the head and they are preferably rounded as shown. It is understood, of course, that a brake head and a brake shoe are hung in a substantially upright position and when the key is driven in place in the openings in the lugs it will bear upon the top boss 16, the outer wall of the opening in the top head lug, the outer wall of the opening in the shoe lug, the outer wall of the opening in the bottom head lug and the bottom boss 16, and it will be bent

between these bearing points sufficiently to secure the shoe tightly on the head so that whatever movement it has relative to the head will be reduced to a minimum and the wear of contacting parts correspondingly reduced. I prefer to pro-

vide two bosses to make the shoe interchangeable end for end and because two bosses will more effectively wedge the key in the lugs than one boss but for some purposes and with some shoes 5 and heads one boss may be sufficient. In Figs. 1-3 the bosses are shown as formed by the body metal of the shoe but separate bosses may be cast in the body of the shoe as shown at 17 in Figs. 4 and 5; or the bosses may be formed by bending 10 up a part 18 of the reinforcing back 19 and extending the body metal to form a support 20 therefor, Figs. 6 and 7, and this body metal support may be omitted from the support as shown at 21, Figs. 8 and 9. When the inner side of the 15 brake head is curved, the end of the key will be deflected thereby to its final position as shown in Fig. 1 but for other types of heads it may be desirable to provide a projection forming an inclined bearing 22 on the head for this purpose. 20 The boss 16 has a face 23 substantially perpendicular to the back of the shoe and an outer face 24 which inclines to the back of the body and toward the end of the shoe. This inclined face will guide the end of the key when it is being inserted to fasten the shoe on the head. 25

The invention provides a simple and effective means for ensuring that the key will hold the shoe tightly on the head to prevent a freedom of movement of the shoe on the head which will produce excessive wear of contacting parts. 30 Sometimes the lower lug of the head which carries the weight of the shoe will be almost completely worn away, and in such case the lug on the shoe is subjected to excessive wear. This will be better understood when it is realized that the average life of a brake shoe is from four to five years after it is mounted on its brake head. The wear on the lugs frequently becomes excessive long before the body of the shoe has reached its limit 35 of wear and the looseness of fit between the shoe and the head due to excessive wear of the lugs and the resulting increase in the magnitude of the vibrations between the shoe and the head to which the shoe is subjected in service, and the violence of these vibrations, results in fracture of 40 the body of the shoe and loosening of the parts of the fractured body so that some of them are liable to fall away from the back, and also results in subjecting the back to greater and more violent vibrations which cause it to break and fall away from the shoe with whatever part or 45 parts of the body that may be attached thereto. The bosses also function to hold the shoe in its proper position on the head by co-operating with the lugs to prevent excessive relative movement of the shoe on the head. This is finally effected by the wedging position of the key in the lugs but the bosses co-operate with the key to a material extent in preventing excessive movement of the 50 shoe relative to the head. I do not intend to be understood as meaning that the invention will hold the shoe rigidly on the head because I know that conditions of manufacture will not permit the accuracy of fit which would be necessary to prevent some relative movement under the conditions of service which cause the shoe and the head to vibrate, but the invention will prevent excessive movement of the shoe relative to the head and excessive wear which results from such movement and the damage which follows therefrom. 55 There will be some wear from any relative movement of the shoe on the head and there will be some movement when the parts are made under present conditions of manufacture; but my in-

vention will materially limit the extent of such movement and correspondingly reduce the wear of contacting parts and eliminate the liability of excessive wear and the damage and danger which may result therefrom.

80

I have shown the invention in simple embodiments which I believe will be sufficient for a full understanding thereof, but I do not limit the invention to these particular embodiments and I may make changes in the form, construction and arrangement of parts to adapt the invention to different conditions within the scope of the following claims:

85

I claim:

90

1. The combination of a brake head having spaced lugs thereon, a brake shoe having end lugs, an attaching lug on the brake shoe positioned between the lugs on the head, said head lugs and attaching lug having openings therein forming a keyway, bosses on the shoe between the end lugs and the attaching lug, the faces of said bosses opposite said attaching lug being substantially perpendicular to the back of the shoe and the outer faces of the bosses inclining from the outer ends of the bosses toward the body and the ends of the shoe, said perpendicular faces and the opposite faces of the attaching lug cooperating to receive the head lugs therebetween and to restrict relative endwise movement of the shoe and head, and a fastening key arranged in said keyway, said key bearing against the outer wall of the opening in the attaching lug and the outer wall of the openings in the head lugs and engaging the bosses and being deflected thereby in said lugs to tightly fasten the shoe on the head and to hold the ends of the key clear of the end lugs on the shoe.

95

2. The combination of a brake head having spaced lugs thereon, a brake shoe comprising a body having end lugs and a central attaching lug, said head lugs and attaching lug having openings therein forming a keyway, a reinforced back embedded in the body, parts of the back being distorted to form bosses on the shoe between the end lugs and the attaching lug, said attaching lug and bosses cooperating to receive the head lugs therebetween and to restrict relative endwise movement of the shoe and head, and a fastening key arranged in said keyway, said key bearing against the outer wall of the opening in the attaching lug and the outer wall of the openings in the head lugs and engaging the bosses and being deflected thereby in said lugs to tightly fasten the shoe on the head and to hold the ends of the key clear of the end lugs on the shoe.

100

3. The combination of a brake head having spaced lugs thereon, and a brake shoe having an attaching lug adapted to be arranged between the lugs on the head, said lugs having openings therein forming a keyway, bosses on the shoe spaced from the attaching lug on opposite sides thereof to receive the lugs on the head between themselves and the attaching lug, a fastening key arranged in said keyway, and a projection on the head forming an inclined bearing to be engaged by and to direct the end of the key when driven in the keyway, said key bearing on said bosses and against the outer wall of the opening in the attaching lug and the outer wall of the openings in the head lugs and being deflected thereby to tightly fasten the shoe on the head.
